(57) **CLAIM**

The ornamental design for a safety cap, as shown and described.

DESCRIPTION

FIG. 1 is a perspective view of a safety cap, showing a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view thereof at a certain angle; and,

FIG. 9 is a cross-cut view thereof taken in the direction of line 9-9 on FIG. 6 showing a safety cap.

The broken lines in the drawing depict environmental subject matter only and form no part of the claimed design.
